CLAIM

I claim the ornamental design for the environmental compressor protection assembly, as shown and described.

DESCRIPTION

FIG. 1 is a perspective view of the environmental compressor protection assembly according to the present design with the compressor sleeve closed.

FIG. 2 is a front view of the environmental compressor protection assembly according to the present design.

FIG. 3 is a back view of the environmental compressor protection assembly according to the present design.

FIG. 4 is a top view of the environmental compressor protection assembly with the compressor sleeve closed.

FIG. 5 is a bottom view of the environmental compressor protection assembly with the compressor sleeve closed.

FIG. 6 is a right side view of the environmental compressor protection assembly with the compressor sleeve closed.

FIG. 7 is a left side view of the environmental compressor protection assembly with the compressor sleeve closed.

FIG. 8 is a perspective view of the environmental compressor protection assembly according to the present design with the compressor sleeve open.

FIG. 9 is a front view of the environmental compressor protection assembly according to the present design.

FIG. 10 is a back view of the environmental compressor protection assembly according to the present design.

FIG. 11 is a top view of the environmental compressor protection assembly with the compressor sleeve open.

FIG. 12 is a bottom view of the environmental compressor protection assembly with the compressor sleeve open.

FIG. 13 is a right side view of the environmental compressor protection assembly with the compressor sleeve open; and,

FIG. 14 is a left side view of the environmental compressor protection assembly with the compressor sleeve open.
